UNITED STATES PATENT OFFICE.

RAOUL VENDOME AND HENRI MARCOUX, OF PARIS, FRANCE, ASSIGNORS TO MARCEL FRANCK, OF PARIS, FRANCE.

POCKET VAPORIZER OR SPRAY APPARATUS.

Application filed July 16, 1924. Serial No. 726,405.

This invention relates to improvements in pocket vaporizers or sprays.

Vaporizers wherein the gaseous fluid is expelled over the liquid to cause the latter to ascend under pressure in a tube provided with a perforation behind its end through which the compressed gaseous fluid can pass, are all well known.

The gaseous fluid meeting the liquid towards the end of the tube and inside the same emulsionizes and atomizes it before forcing it out through a suitable opening preceded or not by an inner mixing chamber formed between the two elements.

15 This invention has for its object a device allowing the gaseous fluid to be expelled under pressure above the liquid.

The device consists of a hollow plunger or piston communicating with a cylinder, 20 the bottom of which is provided with an opening, by means of an automatically closed valve, and an elastic member having a tendency to push the piston out of the cylinder, the apparatus being completed by 25 suitable stopping and closing devices.

The accompanying drawings show by way of example one of the manners of carrying into practical effect the pocket vaporizer forming the object of this invention.

30 Fig. 1 is an elevation, Fig. 2 a plan or top view the lid or cover being removed. Fig. 3 is an underside view and Fig. 4 a vertical section and side view on line A—B of Fig. 1. Fig. 5 shows the apparatus in operation.

The plunger or piston is hollow and closed by a plug H serving to fill it up, a gasket Y being interposed and preferably formed of an india rubber washer or of any other 40 flexible material covered over by a cork washer, while to the hole I formed in its lower part is fitted a tube J ending at a suitable height in the piston A.

Upon the bottom K and outwardly of the 45 hole I is screwed a connection L inside of which is arranged a clack valve M having a spring N normally closing the communication between the inside of the piston A and the outside. A tube C fixed to the piston A 50 extends to the lower part of the inside of the piston A on the one hand and in a mixing chamber E on the other hand. This tube has a rearward perforation D before the said chamber E which perforation D has a size depending on the effect to be produced

(vaporization, spraying and the like). The liquid and gaseous mixture exists through an opening F of the projection F' which follows the chamber E and which projects outside in order to close the pocket vaporizer. The piston A may be moved in the cylinder O, the bottom of which has a central opening P and a dished leather washer or cap Q of elastic material is provided to withstand compression between the piston 60 and the cylinder.

A spring R tends constantly to push the piston out of the cylinder, the piston stroke is limited by the piston ring or collar S and the inner cylinder flange T which is notched at U, to receive the projection F' and hold the piston in the cylinder after the manner of a bayonet joint. A tightening washer Z of elastic material closes the opening F when the apparatus is closed.

70 The apparatus operates in the following manner:

The projection on being freed from the notch U allows the spring R to act upon the piston A and pushes it until the parts S and T come into contact. If the piston is empty, it must be filled with liquid by unscrewing the plug H and putting it back into its place after filling.

75 The apparatus is then taken up, the thumb being pressed under the cylinder and the index finger W upon the piston plug H. While pushing the piston into the cylinder, the thumb V closes the hole P. The fluid under pressure in the cylinder lifts the clack 80 valve M and acts through the tube J upon the liquid contained in the piston which is thus expelled through the tube C, the chamber E and the hole F after having been mixed with the gaseous fluid through the 85 hole D. The piston is then allowed to return to its initial position under the action of the spring R as before the first motion and the cycle can recommence.

90 It must be well understood that other details may be taken into consideration without departing from the nature of this invention, thus the shape of the parts, the material used therefor and the resilient members may differ, while the clack valve M 100 and the tube J may be dispensed with as well as the chamber E, the number of notches may likewise vary and so forth.

We claim:

105 Spray apparatus including an air cylin- 110

der, a liquid cylinder movable as a plunger in the air cylinder to compress the air therein, a valve in the bottom of the liquid cylinder to admit the compressed air to such cylinder, an outlet tube in the liquid cylinder terminating in a guard projection exteriorly of the liquid cylinder, and a flange carried by the air cylinder formed with an opening

to admit the passage of said guard there-through, whereupon the relative rotation of 10 said cylinders will hold the cylinders in in-operative interfitting relation.

Signed at Paris, France, this 20th day of June A. D. 1924.

RAOUL VENDOME.
HENRI MARCOUX.
